UNITED STATES PATENT OFFICE.

ERNST LAUSCHKE, OF CHICAGO, ILLINOIS, ASSIGNOR TO BARNHART BROS.
& SPINDLER, OF SAME PLACE.

DESIGN FOR TYPE.

SPECIFICATION forming part of Design No. 18,239, dated April 3, 1888.

Application filed February 18, 1888. Serial No. 264,540. Term of patent 14 years.

To all whom it may concern:

Be it known that I, ERNST LAUSCHKE, a subject of the Emperor of Germany, residing at Chicago, county of Cook, and State of Illinois, 5 have invented and produced a new and original Design for a Font of Printing - Type, of which the following is a specification, reference being had to the accompanying typographical impressions, which are exact representations of said design.

This design consists of upper and lower case letters, bracket and ornament, points, figures, and dollar-mark. Its general character is considerably extended, of medium weight, rendered rudely and somewhat grotesquely ornate by reason of all lines being irregular, and of uneven width. It is specially marked by the form of the ovals of lower-case a and p and capital D, said ovals being changed from the regular 15 form into irregular helices, such helix being in lower-case a joined at its upper end only to the stem, and the helix in lower-case p being joined at its lower end only to the stem, and the helix in capital D being joined at its upper end only 20 to the stem, this mode of connecting to the stem being the reverse of that which would be natural in striking the letters with a pen by hand. It is further marked by the fact that all ceriphs

are blunt and irregular, and instead of ceriphs capitals U and V have irregular appendages, 30 the former at the left hand and the latter at the right, that of capital V being hooked, making two angles, and that of capital U making but one angle with the stem. A further peculiarity is found in capital G, which has an 35 irregular short cross-stroke at the inner in-turned end of the irregular curve which forms the outline of said letter.

I claim—

The design for a font of printing-type herein 40 shown and described, which is rudely and somewhat grotesquely ornate, of medium weight, considerably extended, with lines irregular and ununiform width, the letters generally having irregular ceriphs, capitals U and V having 45 rude appendages instead of ceriphs, capital G having an irregular cross-stroke at its lower in-turned end, and lower-case a and p and capital D having their ovals irregularly helical, those of a and D being joined to the stems at the upper 50 end only and that of p being joined to the stem at the lower end only, substantially as set forth.

ERNST LAUSCHKE.

In presence of—

E. F. BURTON,
CORA L. CADWALLADER.
